UNITED STATES PATENT OFFICE.

SOLOMON KARPEN, OF CHICAGO, ILLINOIS, ASSIGNOR TO S. KARPEN & BROS., OF CHICAGO, ILLINOIS, A CORPORATION OF WEST VIRGINIA.

SOFA-BED AND DAVENPORT-BED.

1,257,005.

Specification of Letters Patent. Patented Feb. 19, 1918.

Application filed August 9, 1915. Serial No. 44,599.

To all whom it may concern:

Be it known that I, SOLOMON KARPEN, a citizen of the United States, residing at Chicago, in the county of Cook and State of Illinois, have invented new and useful Improvements in Sofa-Beds and Davenport-Beds, of which the following is a specification.

This invention relates particularly to sofa-beds and davenport beds of the type employing an inner folding bed; and the primary object is to provide a structure, of improved and simplified construction and operation, in which the folding-bed is stored in the back of the sofa when the structure is in sofa form.

The invention is illustrated in the preferred embodiment, in the accompanying drawings, in which—

Figure 1 represents a longitudinal sectional view of a combined sofa and bed constructed in accordance with this invention, the structure being shown in extended position; Fig. 2, a broken perspective view showing a portion of one of the bed-sections and a bedding clamp connected therewith; Fig. 3, a broken horizontal sectional view taken as indicated at line 3 of Fig. 1; Fig. 4, a view similar to Fig. 3, but showing the outer portion of the bed, and Fig. 5, a view of the structure in sofa form, one arm of the frame being removed, and the connecting members of the frame being shown in section.

In the construction illustrated, A represents a frame; B, a seat removably mounted therein; C, a folding-bed normally housed in the back portion of the frame; and D, a sofa back comprising a lower section D¹ and an upper section D².

The frame may be of any suitable construction. It preferably comprises standards, or arms, 1, joined by a lower front connecting member 2, an upper back-connecting member 3 and an intermediate back-connecting member 4.

The seat B is carried by a pair of front links, or levers, 5, and a pair of rear links 6. The members 5 are connected, by pivots 5^a, to clips 5^b, which are secured by screws 5^c to the inner surfaces of the frame members 1 a little above and in the rear of the lower front-connecting member 2. The links 6 are carried by pivots 6^a secured to clips 6^b which are connected by screws 6^c to the inner sur-

faces of the lower portions of the arms, or standards, 1 of the frame. The upper ends of the pairs of links 5 and 6 are pivotally connected with the frame of the seat. The lower ends of the front pair of links 5 are extended beneath the pivots 5^a, affording arms which are connected with actuating links 7. The frame of the seat has a depending front member 8, which rests upon the front connecting member 2 of the frame 65 when the structure is in sofa form.

The folding-bed C comprises two main bed-sections 9 and 10 and a spacing section 11. The section 9 is of U-form and has its arms equipped intermediately with forwardly-projecting or offset auxiliary arms, or supports, 9^a, which are mounted on pivots 12 carried by clips 12^a which are connected, by screws 12^b, to the inner surfaces of the standards 1 of the frame A.

When the structure is in sofa form, the bed is folded into U-shape, as shown in Fig. 5, the spacing section 11 being disposed in the upper portion of the back of the sofa-frame. In this condition, the auxiliary, or supporting, arms 9^a of the bed-section 9 extend forwardly and are disposed adjacent the ends of the sofa-seat B. The supporting arms 9^a preferably comprise bars bent edgewise and connected, by rivets 13 85 and 14, to the arms proper of the bed-section 9; said bars are bent into such form as to afford loops, the upper member of the loop being connected with the pivot 12. The front, or web-portion, of the loop is 90 connected, by a pivot 15, to the corresponding link 7, which serves in the actuation of the seat B. Thus the supporting arms 9^a, in addition to forming supports for the folding bed, also serve as levers for shifting the seat B.

When the invention is embodied in a sofa (having a short frame) as distinguished from a davenport bed, the length of the bed extends in a direction at right-angles to the back of the sofa frame. The construction is such as to enable a three-section bed to be employed, the sections 9 and 10 being of unusual width. In such a construction, the section 9 constitutes the 105 head-section of the bed. As stated, it is of U-form having a connecting member, or web, 9^b and the arms proper 9^c, from which the supporting arms 9^a project. Clips 16, which are secured to the inner surfaces of 110

the frame standards 1, and provided with inturned stops 16^a, serve to engage the loops of the arms 9^a when the structure is in extended position, thus preventing the front 5 part of the bed-section 9 from turning downwardly about the pivots 12.

The intermediate, or spacing bed-section, 11, comprises short angle-bars 11^a and a U-shape truss 11^b pivotally connected therewith. The angle-bars 11^a are connected with the extremities of the arms 9^c by pivots 17.

The foot-section 10 of the bed is of U-shape, comprising a web, or cross-member, 10^b, and arms 10^c. The arms 10^c preferably comprise angle-bars and have their extremities connected, by pivots 18, to the members 11^a of the spacing section. The arms 9^c of the head section are likewise 20 angle-bars; and the horizontal flanges of the angle-form bars 11^a overlap the horizontal flanges of the arms 9^c and 10^c when the bed is in extended condition, thus giving the requisite rigidity to the bed frame. The 25 foot-section 10 is provided with folding legs 19 actuated by links 20 which are connected by pivots 11^c to the intermediate bed-section. A wire fabric, or flexible bed-bottom, 21, is applied to the folding frame. 30 The bed-section 9 is shown equipped with a head-piece 22. The foot-section 10 is equipped with a spring-held foot-piece 23 which serves also as a means for clamping the bedding to the foot-portion of the section 10. The member 23 is carried by arms 35 23^a which are connected by pivots 23^b to the arms 10^c of the bed-section 10. Tension springs 24 connect the arms 23^a to the arms 10^c. The arrangement is such that the 40 springs will hold the member 23 in open position, or in the clamping position, after said member is forcibly moved to either one of said positions.

45 The cushion-back D, as indicated, is sectionally constructed. The upper section D² is connected by pivots, or hinges, 25, to the upper cross-member 3 of the frame A. The member D² has an angular shank and is adapted to be swung rearwardly and upwardly to rest upon the member 3. The lower back-section D¹ is connected, by pairs of links 26, to the head-section 9 of the folding bed. When the structure is in sofa-form, the lower edge of the back-section 9 contacts with the rear portion of the seat B; and the lower edge of the upper back-section D² contacts with the upper edge of the back-section D¹.

In converting the structure from sofa-form to bed-form, the upper back-section D² is swung upwardly and rearwardly to rest upon the frame-member 3. The operator then grasps the upper portion of the folded bed, by means of the truss 11^b and turns the bed forwardly about the pivots 12 until

the folded bed is brought to a horizontal position. In this movement, the links 7 carry the seat downwardly and forwardly, thus affording room for the link-carried back-section D¹, which is connected with the head-section 9 of the bed. After the folded bed is turned to the horizontal position, the operator opens, or extends, the bed proper in the usual manner, by swinging the foot-section 10 upwardly and forwardly. In the extended position of the bed, the pivots 12 support the head-section 9, and the stops 16 prevent the outer portion of the head-section from turning downwardly. The bed is thus supported by the arms 9^a of the head-section and the legs 9^b of the foot-section, the joints between the spacing section and main section of the bed being of such a character as to give the required rigidity to the bed frame. 70 75 80 85

In the operation of folding the structure, the outer or foot-section 10 is first folded upon the inner or head-section 9, after which the folded bed is turned about the pivots 12 to bring the bed to the position shown in Fig. 5, and to restore the seat D and back-section D¹ to their proper positions, after which the back-section D² is swung forwardly and downwardly to the position shown in Fig. 5. 95

The construction described is simple, durable, and easily operated. When the bed is folded and disposed in horizontal position, it partially counterbalances itself, because of the position of the pivots 12; counterbalancing springs, are therefore, dispensed with, but may be used if desired. 100

The foregoing detailed description has been given for clearness of understanding only, and no unnecessary limitation should be understood therefrom, but the appended claims should be construed as broadly as permissible, in view of the prior art. 10

What I regard as new, and desire to secure by Letters Patent, is—

1. In a structure of the character set forth, the combination of a frame, a seat, a pair of rear links connecting the seat and frame, a pair of front links connecting the seat and frame and provided with extensions, a folded bed disposed in the rear portion of the frame comprising a plurality of foldably-related bed-sections, one of which is equipped with rigid arms mounted to turn on the frame, link-connections between the bed and the extensions of said front pair of links and adapted to actuate said links, and a sofa-back disposed in front of the upper portion of the folded bed. 115 120

2. In a sofa-bed, the combination of a frame, a seat mounted therein, a folded bed disposed in the rear portion of the frame and having a section equipped with forwardly-projecting rigid arms pivotally connected with the frame, said section being 130

adapted to swing to a position over the seat, other sections foldably related to said first-named section, and a sofa-back comprising a lower section linked to and carried by the 5 first-named bed-section and a swinging upper section connected with the frame.

3. In a structure of the character set forth, the combination of a frame, a link-supported seat, a folded bed comprising a head-section, a spacing section and a foot-section, stored in the rear portion of the frame, arms rigidly connected with and extending 10 forwardly from the head-section and pivotally connected with the frame, links connecting said arms with the links carrying the seat, links connected with the head-section of the bed, a lower back-cushion carried by said last-named links and an upper back-section movably connected with the 15 upper portion of the frame.

4. In a structure of the character set forth, the combination with a frame, a seat, 20

a pair of links connecting each end of the seat with the adjacent end of the frame, the front links having extensions at their lower ends, a folded bed comprising a head-section, a spacing section and a foot section stored in the rear portion of the frame, arms carried by said head-section and projecting forwardly therefrom, pivots connecting intermediate portions of said arms with the ends of said frame, links connecting the front portions of said arms with the extensions of the front seat-supporting links, a pair of links connected with each 25 end of said head-section above the rear portion of said seat, a back cushion carried by said last-named links, and stops carried by said frame and adapted to engage said arms when the structure is in the open position. 30

SOLOMON KARPEN.
